UNITED STATES PATENT OFFICE.

EDWARD H. BINNS AND RALPH H. BINNS, OF PITTSBURGH, PENNSYLVANIA.

SHOE-STRING-HOLDING CUFF.

Application filed May 11, 1922. Serial No. 560,218.

To all whom it may concern:

Be it known that we, EDWARD H. BINNS and RALPH H. BINNS, citizens of the United States, and residents of Pittsburgh, Pa., in the county of Allegheny and State of Pennsylvania, have invented certain new and useful Improvements in Shoe-String-Holding Cuffs, of which the following is a specification.

10 This invention relates to a shoe-string holding cuff, the object of the invention being to make a simple and preferably detachable cuff for shoe tops and to provide the cuff with end shoe-string holders.

15 In the accompanying drawings, forming a part hereof and illustrating the invention, Fig. 1 is a front plan view of a cuff embodying the invention, laid out flat.

20 Fig. 2 is a similar view showing the inner side of the cuff.

Fig. 3 is a sectional detail at line 3—3 of Fig. 4 further illustrating the constructional features of the cuff and of a shoe string holder.

25 Fig. 4 is a perspective view of a lace shoe provided with my new cuff, and

Fig. 5 is a vertical sectional detail at line 5—5 of Fig. 4 showing how the cuff is supported between its ends on the upper edge 30 of the shoe top.

Fig. 6 illustrates a construction in which the shoe-string end holders are directly over the cuff end holes by which the cuff ends are attached to the lacing studs.

35 Fig. 7 illustrates an inside view of what is shown in Fig. 6.

Fig. 8 illustrates the cuff illustrated in Figs. 6 and 7 partially connected with a lace shoe.

40 Fig. 9 is a sectional detail of the shoe-string holding means with which each end of the cuff shown in Figs. 6, 7 and 8 is provided, at line 9—9 of Fig. 7.

In the illustrated form of the invention 1 is the cuff, and 2 the end holes by which the ends of the cuff are detachably hooked on the uppermost lacing studs 3 of the front opening of the lace shoe shown in Fig. 4. Near 45 each end the cuff is provided with a chambered shoe string end holder 4 of button-like form, having a rearwardly projecting shank forming member 5 which is below or under the center of the holder, the end of the

shank being provided with reversely bendable lips 6 which, when the shank is thrust through an opening in the cuff end, are clinched near the back surface of the cuff, as indicated in Figs. 2 and 3. The upper edge of each chambered holder lies in normal approximate contact with the outer surface of the flexible cuff, and when the shoe-string 7 has been tied each of its ends may be inserted in the chamber of a holder by tipping the upper edge thereof forwardly and tucking each shoe-string end into the chamber of a holder. Preferably, the side wall of each holder is formed with an opening 8 towards the front opening of the shoe, so that the shoe-string end portions may be extended more neatly into the holder chambers.

Between its ends this preferably detachable cuff is supported on the upper edge of the shoe top by the under edge of a fillet 9 which extends lengthwise of the inward, upward margin of the cuff. The under edge of this fillet or bearing strip 9 is shown resting on the upper edge of the shoe top 10, in Fig. 5.

As shown in Fig. 6, the shoe-string holders 4^a are fixed to the cuff ends over the holes 2 by means of duplex metal tongues 11 and 12 fixed at 13 to each end of the cuff. The free end of each tongue 11 has an open slot 2^a for interlocking with an uppermost lacing stud 3, and the tongue 12 has a stud 14 through a hole 2. Each shoe-string end may be caught around the stud 14 if desired. At any rate, the ends of a knot may be secured back of the holders 4^a which are recessed or chambered on their back side in direct opposition to the end of the cuff.

It will be seen that in the form of shoe-string holder shown in Fig. 3, for example, the chambered holder has its rearward or inward concave or chambered surface directly opposed to the cuff, and is tippable in relation to the exterior surface thereof. The same relation and mode of action are found in the holder structure shown, for example, in Fig. 9.

What we claim is:

As a new article of manufacture, a shoe cuff provided at its upper inner margin with a lengthwise extending fillet forming a shoulder to rest on the shoe top, and provid-

ed at its ends with holes for attachment to opposed lacing studs adjacent the front foot opening of a shoe, each end portion of the cuff being provided with a rearwardly recessed shoe-string holder; the inner surface of the recessed holder being directly opposed to the cuff surface and being tippable

in relation thereon for reception of a shoe-string end.

Signed at New York city in the county of ¹⁰ New York and State of New York this 27th day of April A. D. 1922.

EDWARD H. BINNS.
RALPH H. BINNS.
